LEAF FEEDING ATTACHMENT FOR TOBACCO STEMMING MACHINES

Application filed August 13, 1929. Serial No. 385,515.

The present invention relates to certain improvements in tobacco stemming or stripping machines, and is especially adaptable to be used with my co-pending application Serial No. 379,204, filed July 18, 1929, and to that type of machine having stem pulling means, leaf conveying means, stem engaging means, and stem and leaf stripping means.

The particular object of the present invention is the provision of positive aligning means for the tobacco leaves upon their introduction to the mechanism of the stemming machine.

A further and important object of the present invention is to provide positive tobacco leaf feeding means for the purpose of presenting the tobacco leaves to the mechanism of the stemming machine in a positive manner, particularly for the purpose of preventing the leaves from moving or sliding out of registered position relative to the mechanism of the stemmer, particularly the mechanism forming the initial operation of the stemming machine, thus permitting the stemming machine to function with a maximum percentage of efficiency.

A still further and particular object of the present invention is the provision of means for positive separation of the tobacco leaves, and preventing the same from grouping and being fed into the stemming mechanism of the machine, more than one leaf at a time.

A still further important object of the present invention is the provision of means for causing the separated tobacco leaves, before being fed to the initial operation of the stemmer, to be substantially equally spaced.

Another and further object of the invention is the provision of means for increasing the spacing between the tobacco leaves, over and above their original spacing when being initially separated by the leaf feeding mechanism, specifically for the purpose of preventing the possibility of crowding of the leaves at any stage of the various operations of the stemming machine.

A still further object of the present invention is to provide means on the tobacco leaf feed and separator sprockets to prevent the crushing or breaking of the tobacco

leaf or its stem, thus allowing for a greater efficiency in the operation of the stemming machine, and particularly that portion of the operating mechanism that is dependent on the wholeness of the stem for its efficient functioning, such as the stemming operation. 55

In the functioning of a tobacco stemming machine, it is the practice of the operator in feeding the machine to place a bundle of tobacco leaves on the feed table of the machine, then by shifting them about by hand he causes the leaves to become separated from the bundle, simultaneously he attempts to align these leaves to the best of his ability 60 while the same are in motion and moving towards the feed mechanism or initial operating mechanism of the machine, thus it is readily seen that it is literally impossible to cause the leaves to move into the machine 65 in any semblance of alignment and proper spacing by depending on the human element for the proper handling of the leaves at this point of the machine. 70

It is another object of the present invention 75 to provide a positive operating mechanism to take the place of the human element in properly aligning, feeding and spacing the leaves preparatory to their initial introduction to the stemming operation of the stemming machine, thus allowing for increased 80 speed, and maximum efficiency in operation of the machine.

With these and other objects in view, the invention consists in certain novel features, 85 arrangement and combination of parts as will be hereinafter more fully described, illustrated in the accompanying drawings, and claimed.

In the accompanying drawings I have illustrated an automatic aligning, feeding and spacing mechanism for a tobacco stemming machine, embodying the various features of my invention in their preferred form. 90

In the drawings, 95

Figure 1 is a side elevation of a fragmentary portion of a tobacco stemming machine, showing the present invention applied thereto;

Figure 2 is a continuation to the left of 100

the illustration, as shown in Figure 1, disclosing the balance of the feed table structure;

5 Figure 3 is a fragmentary view in plan of the invention as shown in Figure 1;

Figure 4 is a plan view of Figure 2 and is a continuation of Figure 3, disclosing the feed table structure;

10 Figure 5 is a fragmentary end view of the invention, as shown in Figure 1, and taken at right angles thereto;

Figure 6 is a fragmentary sectional view on the line 6—6 of Figure 3, illustrating the tobacco leaf feed rollers and space roll;

15 Figure 7 is an enlarged sectional view taken at right angles to Figure 6, illustrating the space roll structure, together with the position of the feed belt co-operating with the same;

20 Figure 8 is an elevation of the toothed distributor roll, for distribution of the tobacco leaves into the feed mechanism;

Figure 9 is a similar view of the toothed spacer roll for properly spacing the tobacco leaves before entering the stemming mechanism of the machine; and,

25 Figure 10 is a fragmentary sectional view, partly diagrammatic, of the feed table and action of the leaf aligning brush member.

30 Referring to the drawings by numerals, the invention as disclosed consists of a tobacco leaf aligning member 1, which in the present instance is in the form of a brush 2, having a substantially rigid bristle portion

35 3, for purposes of contacting the tobacco leaf in the aligning operation, which will be more specifically hereinafter described. Mounted on the frame work 4 with the leaf aligning member 1, is a leaf feed mechanism 5, having

40 a leaf distributor member in the form of a toothed pulley 6, and a tobacco leaf spacer in the form of a toothed pulley 7. The frame work 4 may be mounted on the stemming machine feed table portion 8 of the stemming

45 machine 9, as shown in Figure 5. The tobacco leaf aligning, distributor, spacer and feed mechanism are so placed on the feed table of the stemming machine as to co-operate with the initial feed belts 10 of the feed

50 table 8 and the conveyor belts 11 of the operative portion of the stemming machine. The belts 10 may be carried on the pulleys 14 and 15, and the same receive their operative power through the shaft 16, sprocket 17, sprocket

55 chain 18 and sprocket 19 carried on the shaft 20. This shaft in turn may be powered through the chain of sprocket gearings 21 and 22, which in turn receive their power through the gearing 28 and gearing 23, as

60 shown particularly in Figure 3. The shaft of the worm 24, as indicated at 25, may lead to the original source of power for operating the stemming machine. The conveyor belts 11 carried on the pulleys 26, are also operated through the shaft 20, sprocket gearings

21 and 22, gearing 28 and the worm gearing 24.

Referring particularly to Figures 1, 3 and 5, the leaf aligning brush member 1 receives its operative power through the drive pinion

70

carried on the shaft 25, the drive pinion engaging the gear 30, carried on the shaft 31, which in turn carries the bevel gear 32, which

75

drives a similar bevel gear 33, carried on the shaft 34, at the end of which is a crank 35, which may be fixed to the shaft by means of

80

the key 36. The end of the crank 37 has pivoted thereto, the extension arm 38, which may be T-shaped at its opposite end 39, for

85

the purpose of carrying the threaded portion of the brush supporting rod 40. This rod may be fixed in its relation to the T-shaped

90

portion 39 of the extension arm 38, by means of nuts 41 and 42. The threaded portion of

95

the aligning brush supporting rod 40 is for the purpose of adjusting the height of the brush in its relation to the tobacco leaf feed

100

belts 10, which adjustment also determines the amount of pressure between the bristles of the brush and the contacting surface of the tobacco leaf. Thus, with this type of adjust-

105

ment it is possible to obtain the necessary amount of brushing effect on the top surface of the tobacco leaves as they pass within the operative zone of the brush without unneces-

110

sarily injuring the fibre of the tobacco leaf or the stem thereof.

As will be seen particularly in Figure 5, the extension arm 38 has pivoted thereto, at 100

43, a link member 44, which in turn is piv-

oted at its opposite end 45 to the frame 4. The combined action of the rotation of the crank member 35 and the swinging action of the link member 44, cause the extension arm

105

38 and the aligning brush 1 to move in a path as indicated diagrammatically by a dotted line 46, as shown particularly in Figure 10. The direction of the movement of the bottom

110

line 47 formed by the bristles 3 of the brush member 1, is indicated by arrows in the above

115

mentioned figure. It will be seen that as the bottom surface of the bristles represented by the line 47 near the upper surface of the tobacco leaf the same has a tendency to give

120

a brushing effect to the tobacco leaf transversely to the feeding movement thereof and causing the same to move up to and in contact with the adjustable gauge member 48. This member 48 is adjustable through the butterfly

125

nuts 49, and the slots 50 in the bottom foot of the gauge. As may be readily seen in the

130

plan view Figure 3, the group of tobacco leaves, as indicated in fine dotted lines at 51, are shown as they would ordinarily be placed by hand on the feed table 8 of the stemming

135

machine, preparatory to feeding them into the machine for the stemming action. Thus it will be seen that the position of the stems of the leaves are irregular in their relative position with the gauge member 48. As the

leaves move forward, as indicated by the arrows, and come within the active zone of the aligning brush 1, they are moved over and into positive contact with the gauge surface 52, thus placing the stems of the leaves in position for uniform operation of any function of the stemming machine on this part of the tobacco leaf.

In the usual speed of feeding the leaves 10 to the feed table by hand the leaves have a tendency to become grouped and to overcome this grouping the invention is provided with a toothed pulley 54, which is rotated by the feed belt 55, driven by the pulley 56 carried 15 on the shaft 57, which in turn is rotated by means of the sprocket 58, sprocket chain 59 and sprocket 60, carried on the shaft 61. This shaft 61 is powered through the sprocket and chain member 22. The gearing ratio between 20 the sprocket 60 and the sprocket 58 is approximately one to two, so that the toothed pulley 54 is rotated at a relatively greater speed than the feed belts 10 and the speed of the leaves of tobacco. This excess of speed 25 of the toothed pulley 54, together with the number of teeth in the toothed portion thereof, has a tendency to pull the first leaf of a group that presents itself to the teeth of the pulley at the speed at which the group of 30 leaves are moving up to this point so that as each successive leaf of a group of leaves comes in contact with a toothed portion of the pulley 54, they are literally torn away from the leaves of the group to which they may be 35 adhering. This speed action of the toothed pulley causes the leaf to be thrown into the feed wedge portion 65 formed by the lower feed belt 10 and the upper toothed pulley belt 55. The leaves, after passing into the 40 feed wedge 65, are moved into the path of a second toothed pulley 66, having approximately half the number of teeth as the preceding toothed pulley 54, and moving at substantially twice the rate of speed of the preceding toothed pulley. Thus, when the 45 leaves strike this moving toothed pulley with substantially half the number of teeth of the preceding toothed pulley, the speed of the forward movement of the tobacco leaves is 50 stepped up to the exact ratio of the different speeds of the toothed pulleys and the number of teeth carried on same. Thus the tobacco leaves are caused to be properly spaced in a predetermined manner before entering the 55 operative portion or mechanism of the tobacco stemming machine. This predetermined spacing of the leaves prevents crowding of the same at any given point of operation in the stemming machine and tends to 60 toward uniform action with possibilities of greater speed because of the more uniform distribution of the operative load on the machine.

The toothed pulley 66 is carried on the 65 shaft 67, and is caused to rotate by means of

the belt 68, through the drive pulley 69, which is carried on the shaft 70, which shaft is rotated by means of the sprocket 71, sprocket chain 72 and sprocket 73, carried on the shaft 61. The drive belt for the toothed pulley 66 is extended over and above the belt 75 by means of the idling pulleys 76 and 77, for the purpose of retaining the spaced tobacco leaves in their predetermined spaced position through its co-action with 75 the feed belt 75 and also for the purpose of carrying the leaves up to a point where the lower conveyor belt 78 and the upper conveyor belt 79 may fully take hold of the leaves for the purpose of conveying them 80 through the various stemming operations of the stemming machine.

To assist and co-operate with the action of the feed belts 68 and 75, the invention is provided with an auxiliary set of feed pulleys 85 80 and 81, which are driven by the drive pulley 82 through the drive shaft 70. These pulleys operate the auxiliary feed belt 83, which has a co-action with the lower conveyor belt 78. As will be seen in the plan view of 90 Figure 3, the tobacco leaves, when being fed in a forward direction into the stemming machine by the co-action of the two groups of conveyor belts 68, 75 and 83 and 78, respectively, the tobacco leaves are anchored at two 95 given points of their length, thus preventing any angular, skewing or disalignment of the leaves when being fed forward into the operative portions of the machine.

As will be noted particularly in Figures 7, 100 8 and 9, which show detailed illustration of the toothed pulley members 54 and 66, the teeth of these members, which come into positive and direct contact with the tobacco leaves are made up of a fibrous material 105 85, such as leather or the like, for the purpose of preventing any injury or breakage to the tobacco leaves or the stems thereof, due to the functioning of these members. The fibrous material may be positioned against 110 the face of the pulley by means of a metallic ring 86, which is held tight against the surface of the fibrous material by means of the screws 87. Referring to Figure 5, the various 115 positions of the aligning brush member 1 have all been shown in fine dotted lines for the purpose of clarity and to prevent the obscuring of the various belts and toothed pulleys directly in the path of the aligning brush member 1.

Having thus described my invention, what I claim as new is:

1. In combination with a tobacco stemming and stripping machine, leaf feeding means, means for positively moving leaves 125 to align their butts, means within the path of said aligning means for the purpose of disintegrating groups of leaves into single leaf units, means in the path of and co-operating with said disintegrating means for the 130

purpose of spacing said single leaf units before being conveyed into the operative portion of said tobacco stemming and stripping machine.

5 2. In combination with a tobacco stemming and stripping machine, leaf feeding means, an adjustable gauge member co-operating with positive leaf aligning means for the purpose of predetermining the position of said leaf in relation to the operative portion of said tobacco stemming and stripping machine, means within the path of said aligning means for the purpose of separating groups of aligned leaves into single leaf units, means in the path of and co-operating with said separating means for the purpose of separating said single leaf units at predetermined distances one from the other before being conveyed into the operative portion of said tobacco stemming and stripping machine and positive conveying means for conveying said single leaf units into said machine, as and for the purpose as hereinbefore described.

25 3. In combination with a tobacco stemming and stripping machine, leaf feeding means and an adjustable gauge member co-operating with positive leaf aligning means for the purpose of predetermining the position of said leaf in relation to the operative portion of said tobacco stemming and stripping machine, means within the path of said aligning means for the purpose of separating groups of aligned leaves into single leaf units, means in the path of and co-operating with said separating means for the purpose of preventing the disalignment of said aligned leaf units and means for separating said single leaf units at predetermined distances one from the other before being conveyed into the operative portion of said machine, and means for positive conveyance of said leaf units into said tobacco stemming and stripping machine.

40 45 4. In a leaf conveying machine, leaf feeding means, an adjustable gauge member co-operating with positive leaf aligning means for the purpose of predetermining the position of said leaf in relation to a predetermined point, means within the path of said aligning means for the purpose of separating groups of aligned leaves into single leaf units, means in the path of and co-operating with said separating means for the purpose of increasing the spacing between said single leaf units, means for preventing injury to the leaves when being separated into single leaf units, means for preventing injury to the leaves when passing through the operation of increasing the distances between the single leaf units, and means for conveying said leaves to a predetermined position.

50 55 60 65 5. In a tobacco stemming machine, in combination, a leaf conveying belt, a butt aligning gauge parallel therewith, means to move

leaves longitudinally, across said belt and their butts into contact with said gauge comprising a brush, and driving means for moving said brush toward said gauge in contact with the leaves and away from said gauge out of such contact.

6. In a tobacco stemming machine, leaf butt aligning means comprising in combination, an aligning gauge, a brush for moving leaves to a position with their butts contacting said gauge, a lever supporting said brush, a link pivoted at one end to said lever intermediate the ends thereof, a fixed pivot for the remaining end of said link, a crank for driving said lever connected thereto beyond said link pivot from said brush, and means to drive said crank.

In testimony whereof he hereunto affixes his signature.

LOUIS H. ZEUN.
